UNITED STATES PATENT OFFICE.

CHARLES E. BRADSHAW, OF WATERBURY, CONNECTICUT, ASSIGNOR TO ROBERT N. BASSETT COMPANY, INCORPORATED, OF SHELTON, CONNECTICUT, A CORPORATION OF CONNECTICUT.

BUTTON-CLASP.

1,222,724.

Specification of Letters Patent. Patented Apr. 17, 1917.

Application filed March 29, 1916. Serial No. 87,511.

To all whom it may concern:

Be it known that I, CHARLES E. BRADSHAW, a citizen of the United States, residing at the city of Waterbury, in the county of New Haven and State of Connecticut, have invented a certain new and useful Improvement in Button-Clasps, of which the following is a specification.

My invention relates to metal mountings for running webbing, but more particularly to button clasps for hose supporters of the style which are provided with pivoted links or loops for attaching the same to their supporting webbing, and its object is to produce such a clasp in which the button loop and attaching loop can be assembled by hand thereby dispensing with the employment of the usual assembling machinery.

I attain these and other objects of my invention in the device set forth in the following description and accompanying drawings in which like reference characters refer to corresponding parts.

In the drawings:

25 Figure 1 is a front view of my clasp carried by the lower extremity of a supporting webbing;

Fig. 2, a central vertical section taken on line $x-x$ in Fig. 1;

30 Figs. 3 and 4, front and side views showing the parts partially assembled;

Fig. 5, a front view of a modification;

Fig. 6, a central, vertical sectional view taken on line $y-y$ in Fig. 5, and

35 Figs. 7 and 8, detail views showing the process of assembling the parts shown in Figs. 5 and 6.

The button clasp, which is shown depending from a fold in the extremity of the supporting strap A, consists of an attaching loop B, a button loop C, and a button tab or tape D which carries a button E at its lower extremity. The button loop C, which is connected to the lower side of the loop B by a bearing sleeve F projecting from the upper side thereof, is provided with a bridge G and has the sides of its lower extremity contracted to engage the shank of the button E. The device thus far described is one of the common forms of button clasps well known in the art and is merely disclosed for the purpose of showing how my invention is applied. The attaching loop B is formed out of wire the extremities of which terminate in the pintles 2, 2. The portions

of the loop immediately beyond and to one side of the outer ends of the pintles are flattened or otherwise reduced in thickness as shown at 3, 3. The button loop C is made out of sheet metal and is provided with a projecting strap at its upper extremity which, before the parts are assembled, is curled into a sleeve or pintle bearing F. In forming this pintle bearing the edge 4 of the strap is separated from the body portion sufficiently to leave the slot or opening 5 lengthwise of the bearing from end to end on its under side. To assemble the attaching and button loops the former is first reversed or turned over and one of the flattened portions 3 is passed into and through the slot 5 in the bearing, the pintles 2, 2 at the same time passing into the bearing. When the flattened portion 3 of the attaching loop has been passed through the slot in the bearing the loop may be turned upwardly to the position shown in Fig. 1, thereby bringing the flattened portions 3, 3 out of alinement with the slot 5 so that the parts can not become disassembled without again reversing or turning down the loop. The button tab D may be then attached to the clasp in any desired manner, but preferably by folding the same around the bearing as shown.

It is not necessary that the bearing should be carried by the button loop since the same may be carried by the attaching loop, a particular instance being shown in Figs. 5 and 6 in which the clasp consists of an attaching loop 6, a button loop 7 and a double-ply tab 8. The attaching loop is bent up out of a single piece of wire so that the extremities of the wire will terminate in the lower side 10. The button loop is also bent up out of a single piece of wire so that the wire will terminate in its top side forming inwardly projecting pintles 11, 11. The extremities 12, 12 of the wire forming the lower side 10 of the attaching loop are bent downwardly 100 and, before the parts are assembled, are rolled into alined sleeves 13, 13 which form bearings for the pintles 11, 11. These extremities 13, 13 of the wire forming the lower side of the attaching loop are preferably flattened into straps and when they are curled to form the bearings their end edges are separated from the downwardly projecting portions 12 sufficiently to leave a slot 14 through each bearing from end to 110

end on its top side. The portions of the button loop to one side of the outer extremities of the pintles 11, 11 are reduced or flattened as shown at 15, 15. To assemble the parts 5 the button loop 7 is reversed and placed against the front of the attaching loop 6 to one side of the bearings so that the flattened portions 15, 15 are in alinement with the slots 14, 14 of the bearings. The inner flattened portion 15 of the button loop is then 10 passed through the slots 14, 14, the pintles 11, 11 at the same time passing into their proper positions in the bearings. The loop 7 is then turned down as shown in Figs. 5 15 and 6. The tab 8 may be fastened to the clasp in any desired manner, one way being to pass it through the opening between the extremities of the pintles 11, 11 and draw it tightly around the pintles before the 20 vice is assembled so that the layers of the tab, which are very thin, will readily pass into the slots in the bearings during the assembling operation.

In assembling my device in the manner 25 above described not only the expense of the presses or other machinery usually employed for this purpose is eliminated, but it enables the assembling to be done outside of the factory where the metal parts are made and 30 further it enables the separate parts to be made in different factories, so that one concern may furnish the sheet metal parts and another concern the wire parts and a third concern assemble the parts. It should be 35 further noticed that should the occasion arise for disassembling the parts this operation may also be performed by reversing one of the parts in the same manner as described for the assembling operation.

While I have herein described my invention as applied to button clasps for hose supporters yet the same may be embodied in any articulated metal mountings for running webbing which may fairly come within the scope of the appended claims. 40

Having now described my invention what I claim and desire to protect by Letters Patent is:

1. In a hose supporter or like article two loops and a bearing carried by one of said loops having its side provided with an opening from end to end, the other loop having a pintle bar journaled in said bearing and a flattened portion to one side of and beyond one end of said pintle bar, whereby the 50 pintle bar may slide into said bearing when the parts are being assembled.

2. A hose supporter clasp comprising a lower loop having a bearing which is open on its under side from end to end and an 60 upper loop having a pintle bar journaled in said bearing, the said upper loop having alined flattened portions to one side of and beyond the ends of said pintle bar whereby the 65 pintle bar may slide into said bearing when the parts are being assembled.

3. A metal mounting for running webbing comprising two articulated members one of which is provided with a sleeve having a lateral opening, and the other member having a pintle carried by said sleeve and a flattened portion to one side of said pintle, the 70 said flattened portion being arranged to pass through said opening when the members are being assembled. 75

In testimony whereof I have hereunto set my hand this 31st day of January, 1916.

CHARLES E. BRADSHAW.
